UNITED STATES PATENT OFFICE.

JOHN TEDELL, OF ROCK ISLAND, ILLINOIS, ASSIGNOR TO ROCK ISLAND PLOW COMPANY, OF ROCK ISLAND, ILLINOIS, A CORPORATION OF ILLINOIS.

FEEDING MECHANISM FOR FURNACES.

1,088,379.

Specification of Letters Patent. Patented Feb. 24, 1914.

Application filed June 3, 1912. Serial No. 701,224.

To all whom it may concern:

Be it known that I, JOHN TEDELL, a citizen of the United States of America, and resident of Rock Island, Rock Island county, Illinois, have invented a certain new and useful Improvement in Feeding Mechanism for Furnaces, of which the following is a specification.

My invention relates to a continuous feed for furnaces, and relates more particularly to means whereby bars may be fed step by step through a furnace at the will of the operator.

My invention relates more particularly to a furnace for heating metal bars preparatory to forging, and has been designed with particular reference to treatment of plow beams whereby they are properly heated before being subjected to a bulldozer for bending them into proper shape.

These and other objects of my invention will be more clearly understood by reference to the accompanying drawings, in which similar reference characters refer to similar parts, and in which—

Figure 1 is a front view of a furnace comprising my invention. Fig. 2 is a sectional view taken on line 2—2 of Fig. 1. Fig. 3 is a side elevation. Fig. 4 is a plan view. Figs. 5 and 6 are detail views. Fig. 7 is a sectional view taken on line 7—7 of Fig. 5.

As illustrated, I have shown a furnace comprising a heating chamber consisting of an upper section 11, end walls 12 and 13, and side walls 14, 14. The end walls terminate a short distance above the work support 16, which extends through the furnace and for a distance to the rear thereof, so as to provide suitable space for feeding the bars onto this support. In order to facilitate this feeding operation the rear end of this work support is inclined upwardly, so that the bars can be placed upon this inclined portion and fed by gravity onto the horizontal portion in a manner to be hereinafter more fully described. Situated below this work support there is a cradle 17 which is adapted to be raised and lowered in order to advance the bars step by step along the work support. This cradle comprises a pair of longitudinally extending supporting bars 41—42 which are U-shaped in cross-section, as shown in Fig. 7, so that they fit over the frame bars 43, which frame bars are connected at their opposite ends by the tie rods

44. Near their opposite ends these supporting bars are provided with downwardly extending projections 18 and 20, while extending downwardly from the frame bars are a corresponding pair of supporting arms 45, 46, which arms are connected at their lower ends to the crank arm 19. Rigidly connected to these supporting arms at a distance slightly below the cradle, there are a pair of longitudinally extending braces 39 supported by means of the angular braces 40. Adapted to slide upon each of these longitudinal braces 39 there are a pair of slotted wedges the shape of which being clearly shown in Fig. 6. Each pair of these wedges is connected together by means of a turnbuckle 38, and the inclined faces 47—48 of these wedges are adapted to bear beneath the lower edge of the downwardly extending portions 18 and 19 of the cradle, which extensions are oppositely beveled. The supporting arms 45—46 pass through the slot within these wedges, while a pair of pins 49 and 50 are provided upon opposite sides of the frame bars 43 to prevent the cradle from having any longitudinal movement upon this frame. By this construction it will be seen that by moving the wedges by means of the turnbuckle the top of the cradle can be raised or lowered with respect to the frame, and therefore with respect to the feed support 16. It will also be noticed that I provide a turnbuckle and pair of wedges upon each side of this cradle, so that the opposite sides can be adjusted independently for a purpose which will be more fully pointed out hereinafter.

The opposite ends of the crank arms 19 and 21 are connected to the transversely extending shafts 22 and 23. Upon the end of each of these shafts there is a bevel gear 24 which meshes with the corresponding gear 25 located upon the longitudinally extending shaft 26. Power is supplied to this shaft by means of the motor 27 which operates through the medium of a worm gear 28, and is controlled by means of the clutch 29 operated by the controlling lever 30. A pair of upright supports 31—32 are provided beneath this cradle, and upon the upper part of the support 21 is pivoted the arm 33 which is provided with a hook-shaped end portion 34 adapted to grip beneath the transverse shaft 22. Upon the opposite end of this arm 33 there is a counterweight 35. A

similar pivoted arm and counterweight is mounted on the upper portion of the standard 32, and co-operates with the transverse shaft 33. These counterweights are so adjusted, that they counterbalance the weight of the cradle 17 so as to lessen the amount of power required to operate the same.

Upon opposite ends of the heating chamber I provide sliding doors 51 and 52 which can be raised by means of the levers 53—54, the weight of these doors being counterbalanced by the counterweights 55 and 56. These doors provide means for closing the ends of the heating chamber in order to enable the same to become initially heated more rapidly, but in the operation of the device they are raised a sufficient distance to permit the work to travel through the heating chamber unimpeded. Any suitable means may be employed for heating this chamber, but I have shown gas burners 57 and 58 which are supplied by means of the air and gas pipes 59—60, all of well known construction.

Having now described the construction of my furnace I will now proceed to describe its operation.

The burners are first lighted, and then in order to more rapidly heat the heating chamber the doors 51 and 52 are first lowered, so as to close the openings in the opposite end of the heating chamber. When this chamber has become sufficiently heated, the doors are raised slightly to permit the work to pass through and likewise to permit the escape of the gases of combustion through these openings. The bars to be heated are then fed upon the rear longitudinal and inclined portions of the work 16 and the handle 30 then operated to throw in the clutch 29, whereby the power is applied to raise and lower the cradle 17 by means of the connections heretofore described. The cradle is adjusted by means of the turnbuckles, so that in its raised position the cradle projects slightly above the work support, so that it picks up the bars placed upon this support and carries them forward a short distance, as is clearly shown in dotted lines in Fig. 5. On account of the rotary movement of the crank arms 19 and 20, each point upon the upper surface of this cradle has a similar rotary movement, so that as this cradle comes in contact with the bars or beams on the work support these beams are raised slightly and carried forward a short distance. By means of the adjustment whereby this cradle can be raised or lowered with respect to the crank arm, the distance which this cradle rises above the work support can be readily determined. It is preferably so adjusted that in each revolution of the crank arm the beams upon the work support are carried forward the thickness of a single beam. Furthermore, by having both sides

of the work support adjustable independently, I am able to feed these beams through the furnace in straight lines because if one side starts to travel slightly faster than the other it is merely necessary to lower that side of the cradle so that the cradle on that side will not advance these bars quite such a long distance upon each operation. When these bars have been fed into the heating chamber so that this heating chamber is substantially filled, the clutch can then be thrown out in order to allow sufficient time for these bars to become properly heated. After this has been accomplished and when the operator wishes to take a beam or bar out of the furnace, he merely throws in the clutch to allow the cradle to be raised and lowered a single time, whereby the bars are all pushed forward so that a bar is forced out onto the extension 61, from which place it can be readily gripped by suitable tongs or the like and carried to a forge or bulldozer to be bent into the required shape. When he wishes another beam, he has but to throw in his clutch and another beam is brought out upon the extension 61. While this machine is in operation the beams are simply fed upon the inclined portion of the support 16, and as the beams upon the horizontal portion are carried forward, the force of gravity is sufficient to carry these beams down the inclined portion onto the horizontal portion where they are adapted to be engaged by the cradle.

It will thus be seen that I have devised a very simple and efficient means for continuously feeding bars or beams through a furnace, and in which it is simply necessary to place the beams upon this inclined portion of the work support and thereafter the feeding is entirely automatic.

While I have shown one specific embodiment of my invention, it will be understood that many modifications and equivalents will readily suggest themselves to anyone skilled in the art, and I therefore do not wish to be limited to such a construction.

What I claim as my invention is:

1. In a furnace, a feeding mechanism comprising a stationary work support, a cradle mounted below said support, and means for raising the upper surface of said cradle above said work support, said cradle having a combined upward and forward movement, whereby the material to be treated is raised from said support and moved forward by said cradle.

2. In a furnace, a feeding mechanism, a work support, a cradle mounted below said support, and adapted to be raised above said support and to be moved forwardly for moving said material along the same, and means for adjusting the position of said cradle with respect to said support.

3. In a furnace, a feeding mechanism, a

work support, a cradle mounted below said support, and adapted to be raised above said support and to be moved forwardly for moving said material along the same, and 5 means for independently adjusting the opposite sides of said cradle with respect to said support, whereby the material is fed evenly along said support.

4. In a furnace, a work support, a frame 10 mounted below said support, a cradle adjustably mounted upon said frame, a crank arm for oscillating said frame and cradle, whereby said cradle has an upward and forward movement, whereby the movement of 15 said cradle causes the work to be treated to be moved along said work support step by step.

5. In a furnace, a feeding mechanism comprising a work support, a frame mounted 20 below said support, a cradle mounted upon said frame, a pair of wedges for supporting said cradle whereby it may be adjust-

ably mounted upon said frame, and means for oscillating said frame and cradle whereby said cradle rises above said work support so as to raise the work upon said support and move the same forward and then replace the work upon the support. 25

6. In a furnace, a feeding mechanism, comprising a work support, a cradle mounted below said support, means including a crank arm for oscillating said cradle, whereby it is raised above said work support to raise the work from said support and move the same forward, and counterweights associated with said cradle, so as to counter-balance the weight of the same. 30 35

Signed by me at Rock Island, Illinois, this 29th day of May 1912.

JOHN TEDELL.
